METHOD AND APPARATUS FOR ELECTRODEPOSITING CHROMIUM

Filed April 30, 1927

UNITED STATES PATENT OFFICE.

KEVIE W. SCHWARTZ, OF NEW YORK, N. Y., ASSIGNOR TO CHROMIUM CORPORATION OF AMERICA, A CORPORATION OF DELAWARE.

METHOD AND APPARATUS FOR ELECTRODEPOSITING CHROMIUM.

Application filed April 30, 1927. Serial No. 187,733.

This invention relates to methods and apparatus for electrodepositing metals, such as chromium, on the inside of hollow articles, connected as cathode, such as pipes, tubes, vessels and the like, and provides improvements therein.

The present invention provides an improved method and apparatus for electrodepositing metals, such as chromium, upon the inside of hollow articles, particularly where there is disengaged in the process of electrodeposition considerable quantities of gas, as for example hydrogen, and particularly where large surfaces are to be coated and the current will be inordinately large in attempting to coat the entire surface simultaneously.

The invention furthermore provides a method and apparatus particularly suitable for electrodepositing metal on the inside of hollow articles in situ, particularly where such articles have a considerable vertical height.

The invention also provides an apparatus particularly adapted to being set up on the inside of hollow articles where the ingress to such articles is through an opening of restricted size.

An embodiment of the invention is illustrated in the accompanying drawing. The invention is illustrated as applied to the electrodeposition of chromium on the inside of a large hollow reaction chamber such as is used in the process of cracking oil.

In said drawings:—

Figure 1 is a vertical sectional view through the reaction chamber, showing the electrodepositing apparatus set up therein.

Fig. 2 is a cross-section on the line II—II, Fig. 1.

Fig. 3 is a cross-section on the line III—III, Fig. 1.

Numeral 10 designates the hollow article which is to be coated on its inner surface with a coating of metal. The vessel illustrated is a large steel vessel such as is used as a reaction chamber in an oil cracking installation, and on which an electrodeposit of chromium is to be produced on its inner surface. These reaction chambers are usually quite large, typi-

cal dimensions being 30 to 40 feet in height 50 and 10 feet in diameter. These reaction chambers are usually provided with restricted openings 12, 13 of a few feet in diameter at top and bottom. Many of these reaction chambers are set up in installations, and it 55 is desirable to be able to electrodeposit the coating metal with the vessel 10 in situ.

The preferred coating metal is chromium. Any suitable solution for electrodepositing the chromium may be used. I prefer, however, one of the known chromic acid solutions, such for example as disclosed in the Grube Patent, No. 1,496,845, granted June 10, 1924, or in the Fink Patent, No. 1,581,188, granted April 20, 1926. 65

In electrodepositing chromium from chromic acid baths, there is a relatively large disengagement of hydrogen which is released from the cathode surface as a gas, and the current densities used are relatively large. 70

To attempt to electrodeposit chromium simultaneously over the entire inner surface of a vessel having the given dimensions of the vessel 10 would, under ordinary conditions, require the use of about 100,000 amperes. 75 Generators of this size would be inordinately large, and in any event it would in most cases be preferable to use generators of less ampere rating.

Furthermore, if it were attempted to electrodeposit chromium on the entire surface at once, the disengagement of the hydrogen would be so great as, under ordinary conditions, to interfere with the deposition being successfully effected over the entire surface. 85

According to the present invention, deposition is effected on a part of the inner surface of the article 10 at a time, and this electrodeposit is progressively extended over or around the entire surface. The portion of 90 the inner surface on which the electrodeposition starts is conveniently a strip or strips running lengthwise of the vessel. This strip extends over portions of the surface which are angularly displaced with relation to one 95 another, the arrangement of such angularly displaced portions with relation to one another being such that the hydrogen or other

gas released at one portion of the cathode surface receiving deposited metal will not interfere with the deposition going on on the adjacent portions of said strip.

- 5 The deposit in the manner just described is conveniently effected by means of an anode structure 20. The portion or portions of the anode structure which directs the depositing current onto the strip of cathode surface undergoing plating at any one time is designated by the numeral 22. The anode part 22 is arranged lengthwise of the strip of the cathode surface which is to be plated, and the anode part 22 is also arranged in
- 10 such manner that portions thereof, as the portions 25, 26, 27, 28, 29, 30, 31, 32, 33, 34, 35, 36, 37, are angularly displaced with relation to one another, the angular displacement being such that the gas released
- 15 at the cathode opposite one portion of the anode will not interfere with the deposition in the active zone or area of the adjacent anode portions. The anode part 22 may in whole or in part have the characteristics of
- 20 a spiral or sinuous shape. The anode portions 25 et seq. are preferably made in separate portions or sections, as illustrated. Such separate construction facilitates the manufacture and assembling of the anode structure, particularly where this is to be done on the inside of a hollow vessel where the ingress is restricted. The shape and area of the anode part 22 and of its portions 25 et seq.,
- 25 may be chosen to best suit the conditions of
- 30 the current densities, gas disengagement, facilities for removing the gas, and the size of openings encountered in the particular job to be carried out.

- 35 The cathode strip on which the metal is deposited is broadened progressively until the required or entire surface is covered with the electrodeposited metal. To this end, means are provided for effecting relative movement of the anode and cathode. Preferably the anode part 22 is mounted upon a rotatable shaft 40, the part 22 being conveniently attached to said shaft 40 by a plurality of arms 44. These arms 44 are detachably connected to the shaft 40 by means of separable hub portions 46 (Fig. 3), so that the arms and anode part 22, where such latter part is in plurality of sections 25 et seq., may be passed separately through the opening, as the opening 12 in the vessel 10.
- 40
- 45
- 50
- 55

- 55 The shaft 40 is rotated in suitable manner, as by means of a worm and gear drive 48. The shaft 40 may, as here shown, be made hollow (see Figs. 2 and 3) and electrical conductors 50 leading through said hollow shaft
- 60 to the several anode portions 25 et seq. The several conductors 50 may be connected to a ring 52, in contact with the plus side of a generator through the brushes 54.

Means for maintaining the temperature of

the solution approximately constant may be provided. Conveniently, these comprise pipe connections 60, 61, by means of which a circulation of the electrolyte into and out of the vessel may be provided, the incoming solution having a temperature which will give to the solution in the vessel the desired approximately constant temperature.

The vessel itself is used as the container for the solution, and is usually filled to its top. The gas is vented through the upper opening 12 in the tank, and auxiliary means for facilitating the venting may be employed if desired.

The vessel or other hollow article 10 is connected to the negative side of the generator in any suitable manner, as by means of conducting straps 70, 71.

One or more anode parts 22 may be provided. As here shown, the anode part 22 and its portions 25 et seq. have diametrically opposite corresponding sections. The description of one of these anode parts 22 suffices for an understanding of the other or others.

The gas, as it rises, tends to distribute in the body of the electrolyte, so that at a suitable height above or distance away from any particular angular portion, for example the angular portion 36, another portion, as the portion 75, occupying a similar angular position, may be used without substantial detriment.

For plating the end or ends of the vessel 10, suitable anode sections 80 may be provided. These face the end of the vessel, and the end surface deflects the gas rising in the vessel from the cathode surface immediately opposite the anode 80. These anode portions 80 are preferably also arranged so as to deflect the gas toward the outlet 12. Suitable deflectors similar to anode sections 80 but preferably non-contacting, may be provided along the shaft 40 for deflecting toward the center the gas disengaged from and contained in the solution.

The invention may receive other embodiments, and be carried out in other modes of procedure than those specifically herein illustrated and described.

What is claimed is:

1. An apparatus for electrodepositing metals such as chromium on the inside of hollow cathode articles, comprising an elongated anode having angularly displaced portions, whereby the gaseous products released at the cathode opposite one portion of the anode will not interfere with the deposition in the active zone or area of the adjacent anode portions.

2. An apparatus for electrodepositing metals such as chromium on the inside of hollow cathode articles, comprising an elongated anode having angularly displaced portions, whereby the gaseous products released

at the cathode opposite one portion of the anode will not interfere with the deposition in the active zone or area of the adjacent anode portions, and means for moving said anode relative to said cathode surface, whereby the surface of said cathode may be progressively coated.

3. An apparatus for electrodepositing metals such as chromium on the inside of hollow cathode articles, comprising an elongated anode having angularly displaced portions, whereby the gaseous products released at the cathode opposite one portion of the anode will not interfere with the deposition in the active zone or area of the adjacent anode portions, and means for moving said anode relative to said cathode surface, whereby the surface of said cathode may be progressively coated, said means comprising a shaft on which said anode is mounted.

4. An apparatus for electrodepositing metals such as chromium on the inside of hollow cathode articles, comprising an elongated anode having angularly displaced portions, whereby the gaseous products released at the cathode opposite one portion of the anode will not interfere with the deposition in the active zone or area of the adjacent anode portions, and means for moving said anode relative to said cathode surface, whereby the surface of said cathode may be progressively coated, said means comprising a shaft on which said anode is mounted, said anode being made of separate parts or sections, whereby they may be passed through a restricted opening to the interior of the hollow cathode article, and built up in situ therein.

5. An apparatus for electrodepositing metals such as chromium on the inside of hollow cathode articles, comprising an elongated anode having angularly displaced portions, whereby the gaseous products released at the cathode opposite one portion of the anode will not interfere with the deposition in the active zone or area of the adjacent anode portions, and means for moving said anode relative to said cathode surface, whereby the surface of said cathode may be progressively coated, said means comprising a shaft on which said anode is mounted, and means for rotating said shaft.

6. An apparatus for electrodepositing metals such as chromium on the inside of hollow cathode articles, comprising an elongated anode having angularly displaced portions, whereby the gaseous products released at the cathode opposite one portion of the anode will not interfere with the deposition in the active zone or area of the adjacent anode portions, said sections being separated from one another.

7. An apparatus for electrodepositing metals such as chromium on the inside of hollow cathode articles, comprising an elongated

anode having angularly displaced portions, whereby the gaseous products released at the cathode opposite one portion of the anode will not interfere with the deposition in the active zone or area of the adjacent anode portions, and means for venting said gaseous products.

8. The method of electrodepositing metals such as chromium on the inside of hollow cathode articles, comprising directing the depositing current onto the cathode along an elongated strip, portions of which are angularly displaced with relation to one another, and continuing the deposition as a broadening band by progressively directing said current to the cathode surface in like relation.

9. The method of electrodepositing metals such as chromium on the inside of hollow cathode articles, comprising directing the depositing current onto the cathode along an elongated vertical strip, portions of which are angularly displaced with relation of one another, and continuing the deposition as a broadening band by progressively directing said current to the cathode surface in like relation.

10. In a method of electrodepositing metals such as chromium on the inside of hollow cathode articles, comprising directing the depositing current onto the cathode article along a vertical strip, portions of which are angularly displaced with relation to one another, whereby the gaseous products released at one portion of the cathode strip receiving deposited metal will not interfere with the deposition on the adjacent portions of said strip.

11. In a method of electrodepositing metals such as chromium on the inside of hollow cathode articles comprising directing the depositing current onto the cathode article along a vertical strip, portions of which are angularly displaced with relation to one another, whereby the gaseous products released at one portion of the cathode strip receiving deposited metal will not interfere with the deposition on the adjacent portions of said strip, and venting said gaseous products.

12. In a method of electrodepositing metals such as chromium on the inside of hollow cathode articles, comprising directing the depositing current onto the cathode article along a vertical strip, portions of which are angularly displaced with relation to one another, whereby the gaseous products released at one portion of the cathode strip receiving deposited metal will not interfere with the deposition on the adjacent portions of said strip, deflecting said gaseous products toward the center portion of said hollow article, and venting said deflected gases.

13. In a method of electro-depositing metals such as chromium on the inside of long hollow articles comprising standing said ar-

ticles upright with plating solution therein, and directing the depositing current on to the cathode article from an anode in a progressive band or strip circumferentially of said article, and of a height considerably less than the height of said cathode article, whereby the gaseous products released at the lower por-

tion of the cathode strip receiving deposited metal will not interfere with the deposition on the upper portions of said strip.

In witness whereof, I have hereunto signed my name.

KEVIE W. SCHWARTZ.
